UNITED STATES PATENT OFFICE

RAGNAR E. MATHIASSEN, OF PHILADELPHIA, PENNSYLVANIA

COMBINATION LAMP AND STAND

Application filed August 8, 1931. Serial No. 555,988.

The present invention relates to a combination apparatus having incorporated therein the features of a floor lamp, a reading or music stand etc.

5 The prime object of the invention resides in the provision of a combination apparatus of this nature wherein the structure is simple, easy to manipulate, compact and convenient in its arrangement of parts, strong and durable, thoroughly efficient and reliable in use and operation, not likely to easily become out of order, and otherwise well adapted to the purpose for which it is designed.

10 With the above and numerous other objects in view as will appear as the description proceeds, the invention resides in certain novel features of construction, and in the combination and arrangement of parts as will be hereinafter more fully described and 15 claimed.

In the drawings:

Figure 1 is a side elevation of an apparatus embodying the features of my invention showing the shade in section.

20 Figure 2 is a detail horizontal section taken substantially on the line 2—2 of Figure 1.

Figure 3 is an enlarged detail section through the upper portion of the apparatus.

25 Figure 4 is an end elevation of one of the holders.

Figure 5 is an enlarged detail horizontal section taken substantially on the line 5—5 of Figure 3.

30 Figure 6 is a vertical section through the base of the apparatus.

Figure 7 is a top plan view of the spring and spring housing.

Figure 8 is a horizontal section therethrough showing the pawl and ratchet.

35 Figure 9 is a sectional view through a swivel plug.

Figure 10 is a bottom plan view of the upper section thereof.

40 Figure 11 is a top plan view of the lower section thereof.

Figure 12 is a detail section taken substantially on the line 12—12 of Figure 11.

45 Referring to the drawings in detail, it will be seen that the numeral 5 denotes a hollow base formed with the recess 6 therein open

55 at the bottom and continuing through a neck 7 which rises from the base. Numeral 8 denotes a removable closure plate for the bottom of the recess. Numeral 9 denotes a spring housing resting on the plate 8 and having a central pin projecting upwardly therefrom on which is journaled a spool 11. A spring 12 of the coil type has one end anchored to the pin 10 and the other end anchored to the housing 9. This pin 10 is fixed in the spool 11 and is rotatable in the bottom of the housing 9. Below the spring 12 there is fixed on the pin 10 an annular ratchet 13 to cooperate with spring pressed pawls 14 mounted on the bottom of the housing. Numeral 15 denotes an electrical cord windable about the spool 11 and projecting through a radial opening 16 in the base. Thus when the outer end of the cord has been electrical- 60 65 70 75 80 85 90 95 100

ly connected with a source of electrical energy such as through an ordinary floor plug or the like, the base of the lamp may be moved to and from the floor plug or the like a distance depending upon the length of the cord. The cord is caused to wind and unwind on the spool similar to the ordinary spring curtain or shade roller now in common use. In Figures 9 to 12 inclusive I have shown in detail a swivel plug including a bottom section 18 and an upper section 19. The lower section has an annular flange 20 rising therefrom to receive the lower portion of the section 19. The section 19 has an annular shoulder 21 resting on the flange 20 with which spring clips 22 mounted on the section 18 engage.

A central conductor 23 is disposed in the section 18 and has a contact 24 on its upper end engaging a contact 25 on the lower end of a central conductor 26 in the section 19. An off center conductor 27 in the section 18 is engaged with an annular ring 28 on the top of the section 18 a portion of which is curved upwardly at an incline to provide a spring tongue 29 which wipes against an annular ring 30 on the bottom of the section 19 and with which is engaged an off center conductor 31. The conductor 15 is engaged with the conductors 23 and 27. Conductors

26 and 31 are connected respectively to conductors 32 and 33.

A cylindrical like shell 34 rises from the neck 7 and is fixed thereto and the upper end is reduced in diameter as is clearly illustrated in Figure 3 and a bar 35 has its upper end fixed in said constricted upper end of the shell and extends down longitudinally therethrough. The conductor 32 extends 10 through the bar 35. A cap 36 is mounted on the upper end of the shell 34 and a stem 37 is disposed therein extending into the upper end of the bar 35. The conduit or conductor 33 extends through this stem and through 15 arms 38 projecting from the stem and through openings in the cap 36 and having incandescent bulbs 39 mounted on the outer ends thereof in the usual well known manner.

A shade frame 40 on the upper end of the 20 stem 37 above the cap 36 support a frusto-conical shade or the like 41.

On opposite sides of the upper portion of the bar 35 are longitudinally extending dove-tailed grooves 42 in which are slidable dove-tailed shoes 43 and 44. These shoes 43 are 25 adjustable up and down and may be held in different adjusted positions by means of pins 44a extending through openings therein and engageable in notches 45 formed in the kerfs 30 of the grooves 42.

A pair of lazy tongs 46 have their inner ends engaged with shoes 44 and 43 and on their outer ends have hingedly mounted as at 35 47 holders 48 with breakable braces 49 associated therewith. These holders 48 are adapted to hold books, music and the like. An incandescent electric light 50 is mounted on each holder and the conduits 33 lead thereto being trained over pulleys 51 on arms 52 projecting from the shoes 43. If the holders 48 are 40 to be lowered, the pins 44a are removed from beneath the lower shoes 44, and after lowering the lazy tong structures, the pins can be replaced under the upper shoes 44, 45 with the holder 48 in a lowered position beneath the shade 41.

The lazy tongs and the conductors 33 extend through slots 53 provided in opposite 50 sides of the shell 34. The pins 44 are also projected through these slots so as to be accessible from the exterior of the shells. Springs 54 are anchored on the conduits 33 and are anchored in the neck 7 by suitable means 55 so that when the lazy tongs are collapsed the surplus portions of the conductors 33 are housed within the shell as will be quite apparent.

As shown in Fig. 1, the holders 48 are 60 capable of being adjusted toward or away from the shell 34, the lazy tong structures being substantially extended in Figs. 1 and 2.

It is thought that the construction, operation, utility and advantages of this invention 65 will now be quite apparent to those skilled

in this art without a more detailed description thereof.

The present embodiment of the invention has been described in considerable detail merely for the purposes of exemplification 70 since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages. 75 80

Having thus described my invention, what I claim as new is:

1. In combination, a lamp including a shade and a post for supporting the shade, an article holder, a lazy tong structure between the article holder and the post, and a slidable connection between the lazy tong structure and the post whereby the lazy tong structure can be disposed within the confines of the shade when collapsed. 90

2. In combination, a lamp including a shade and a post for supporting the shade, an article holder, a lazy tong structure between the article holder and the post, a slidable connection between the lazy tong structure and the post whereby the lazy tong structure can be disposed within the confines of the shade when collapsed, said post being provided with a slot therein, and blocks on the inner end of the lazy tong structure for riding engagement with the said slot. 100

3. In combination, a lamp including a shade and a post for supporting the shade, an article holder, a lazy tong structure between the article holder and the post, a slidable connection between the lazy tong structure and the post whereby the lazy tong structure can be disposed within the confines of the shade when collapsed, said post being provided with a slot therein, blocks on the inner end of the lazy tong structure for riding engagement with the said slot, said post being provided with a plurality of vertically spaced recesses, one of said blocks being provided with an opening therethrough and a pin disposable through the said opening and into any one of the said recesses. 110 115

In testimony whereof I affix my signature.

RAGNAR E. MATHIASSEN.
